CLAIM

The ornamental design for camera receiver, as shown and described.

DESCRIPTION

FIG. 1 is a perspective view of a camera receiver showing our new design with the antenna in an unfolded position; FIG. 2 is a reduced front elevational view thereof;

FIG. 3 is a top plan view thereof;

FIG. 4 is a left side elevational view thereof;

FIG. 5 is a right side elevational view thereof;

FIG. 6 is a bottom plan view thereof;

FIG. 7 is a rear elevational view thereof; and,

FIG. 8 is a perspective view thereof with the antenna in a folded position.

The broken line showing of a fragmentary cord is to illustrate environment only and forms no part of the claimed design.
